MORGAN J. EVANS, OF MILWAUKEE, WISCONSIN.

DOOR HANGER AND TRACK.

1,041,053.

Specification of Letters Patent. Patented Oct. 15, 1912.

Application filed December 23, 1910. Serial No. 598,914.

To all whom it may concern:

Be it known that I, MORGAN J. EVANS, a citizen of the United States, residing in Milwaukee, in the county of Milwaukee and 5 State of Wisconsin, have invented new and useful Improvements in Door Hangers and Tracks, of which the following is a description, reference being had to the accompanying drawings, which are a part of this specification.

10 This invention relates to improvements in door hangers and tracks particularly adapted for use in supporting sliding doors.

It is one of the objects of this invention to 15 provide a door hanger and track which are strong, efficient, and comparatively light in weight and which may be manufactured at a minimum expense.

20 A further object of the invention is to provide a door hanger and track in which the track portion is formed of sheet metal bent to a flanged tubular shape so that it will withstand the maximum amount of strain in any direction to which it may be subjected.

25 A further object of the invention is to provide a door hanger and track in which the door supported by the hanger may swing longitudinally and laterally of the 30 track to compensate for inequalities of manufacture in erecting the parts.

35 With the above, and other objects in view, the invention consists of the improved door hanger and its parts and combinations as set forth in the claims, and all equivalents thereof.

40 In the accompanying drawing in which the same reference characters indicate the same parts in all of the views: Figure 1 is a side view of the improved hanger and a portion of the track with a part of a door shown suspended therefrom, parts of the hanger and the track being shown in section; Fig. 2 is an end view thereof with the track 45 shown in section; Fig. 3 is a top view of the carriage, parts broken away and other parts being shown in section; Fig. 4 is a side view of a portion of a modified form of hanger; Fig. 5 is fragmentary detail view thereof; 50 Fig. 6 is a fragmentary detail view of one of the parts shown in Fig. 5; and, Fig. 7 is a similar view of another part shown in said figure.

55 Referring to the drawing the numeral 10 indicates a portion of a door frame to which is bolted the track bracket 11. This bracket

is provided with a track engaging sleeve 12 projecting therefrom which is adapted to extend around the tubular track section 13 and securely fasten said track sections to the 60 supporting door frame. The brackets are spaced certain distances apart to provide the requisite support for the track sections and have bolt apertures formed therein to accommodate bolts or lag screws used for 65 fastening them to a building.

The track is formed of sheet metal bent into tubular form approximately rectangular in cross section and having an elongated slot 14 in the lower tread portion 15 thereof which extends the entire length of the track section. The lower edge portions of the track are bent downwardly at right angles to the lower portion to form vertical strengthening flanges 16 and are again bent 70 at right angles toward each other to form horizontal strengthening flanges 17 which are spaced a distance apart to form the lower portion of the elongated slot 14. These horizontal flanges 17 serve to strengthen the 75 vertical flanges against lateral movement. The lower portion of the sleeve of the bracket is provided with a slot 18 to accommodate the depending flanges of the track, and also in order not to obstruct the passage of a 80 hanger member suspended from the inner portion of the track. The vertical strengthening flanges 16 of the track are spaced a greater distance apart than the horizontal flanges 17 in order to provide space in the 85 slot 14 to accommodate the flanges 19 of hanger wheels 20. These wheels are journaled on the roller bearing pins 21 carried by the horizontally projecting arms 22 of the hanger frame 23. The wheels which are 90 interposed between the straddling arms of the hanger frame have double flanges and tread portions and are equivalent to and may be termed double wheels which are integrally connected together by the medial hubs 24 for 95 convenience of manufacture. The wheels are positioned to travel on the tread portions 15 of the track with the flanges thereof extending into the widened portion of the slot and serving as guides to position the wheels and 100 frame centrally within the tubular tracks.

The hanger frame between the pairs of wheels depends downwardly and through the slot of the tubular track in the form of legs 25 having eyed ends 26, the eyes of 110 which are in alinement with each other. A pivot bolt 27 extending through the eyed

ends of the depending frame legs is taperingly reduced in diameter toward each end from a medial enlargement 28, the reduction in diameter ending at the inner faces of the 5 eyed legs in order to have the bearing portions 29 of the bolt of the same diameter as the medial portion 28. The bolt is held in position in the eyed member by means of the head on one end and a cotter pin 30 10 which extends through the bolt at the other end.

A looped hanger strap 31 extending over the portion of the bolt between the depending frame legs and on both sides of a door 15 32 is fastened to said door by bolts or rivets 33. The looped portion of the strap engages the medial enlargement of the pivot bolt and can rock longitudinally thereon as well as turn laterally thus providing a joint 20 construction in which the hanger frames and wheels will be automatically adjusted to and ride over undulations or inequalities of the track.

In the modified form shown in Figs. 4, 25 5, 6 and 7 the pivot bolt 34 is adapted to be adjusted vertically with relation to the hanger frame in order to raise or lower the door suspended from the strap 31. This adjustment is provided for by forming the 30 pivot bolt with upstanding ears 35 having horizontal slots 36 extending therethrough. The lower ends 37 of the depending legs 25 have vertical slots 38 extending therethrough and screw bolts 39 extend through 35 these slots and the slots 38 and are threaded to the nuts 40 bearing against the inner faces of the upstanding ears 35. The upstanding ears are provided with shoulders 41 to hold the nuts in position and prevent 40 their turning while the screws are being turned. The engaging faces of the ears 35 and the lower ends 37 of the legs are serrated or provided with teeth 42 and 43 respectively to hold the parts in adjusted position. The horizontal slots provide for lateral adjustment of the pivot bolt, it being 45 only necessary to loosen the screw bolts and slide the pivot bolt to the desired position and then retighten the screws. In adjusting the bolt vertically the bolt is separated 50 sidewise from the legs and is raised or lowered and then slid back into position with the teeth engaging each other. The screw bolts are then inserted and tightened as before mentioned.

While the hanger frame and legs thereof are shown as formed integral the said frame and legs may be formed of two or more pieces bolted or riveted together.

60 From the foregoing description it will be seen that the hanger and track are very simple in construction and operation and are strong and durable.

What I claim as my invention is:

65 1. A door hanger and track, comprising a

tubular track provided with a lower longitudinal slot, a bracket therefor, a hanger frame positioned within the tubular track and having legs depending downwardly therefrom and through the longitudinal slot, 70 said legs provided with slotted ends, wheels journaled on the hanger frame and bearing on the lower inner portion of the track, a bolt positioned between the depending legs, bolts extending through the slots and engaging the bolt, and a door supporting strap extending between the legs and looped over the bolt and resting to form a swinging connection between the strap and the bolt.

2. A door hanger and track, comprising a 80 tubular track provided with a lower longitudinal slot, a bracket therefor, a hanger frame positioned within the tubular track and having legs depending downwardly therefrom and through the longitudinal slot, 85 wheels journaled on the hanger frame and bearing on the lower inner portion of the tubular track, a member adjustably connected to the depending legs and positioned between the depending legs, and a door supporting strap extending between the legs and looped over the member and resting thereon to form a swinging joint connection between the strap and the member.

3. A door hanger and track, comprising a 95 tubular track provided with a lower longitudinal slot, a bracket therefor, a hanger frame positioned within the tubular track and having legs depending downwardly therefrom and through the longitudinal slot, 100 100 said legs provided with slots and having serrated faces, wheels journaled on the hanger frame and bearing on the lower inner portion of the tubular track, a bolt having slotted ears and serrated faces, 105 said bolt positioned so that its serrated faces will engage the serrated faces of the depending legs and the slots will register with each other, bolts extending through the slots to bind said parts together, and a door supporting strap extending between the depending legs and looped over the bolt thereon to form a swinging joint connection between the strap and the bolt.

4. A door hanger track, comprising a tubular track provided with a lower longitudinal slot, said tubular track having reinforcing flanges depending downwardly therefrom on each side of the slot and extending approximately at right angles inwardly toward each other at their lower edges to reinforce the downwardly extending flanges laterally.

5. A door hanger and track, comprising a 125 tubular track provided with a lower longitudinal slot, a bracket therefor, a hanger frame positioned within the tubular track and having legs depending downwardly therefrom and through the longitudinal slot, flanged wheels journaled on the hanger 130

frame and bearing on the lower inner portion of the tubular track with the flanges extending into the longitudinal slot, a member adjustably connected to the depending legs and provided with a medial enlargement positioned between the depending legs, and a door supporting strap extending between the legs and looped over the member and resting on the medial enlargement to

form a universal joint connection between 10 the strap and the member.

In testimony whereof, I affix my signature, in presence of two witnesses.

MORGAN J. EVANS.
